UNITED STATES PATENT OFFICE.

CHARLES ROWLAND, OF WASHINGTON, D. C., ASSIGNOR TO JAMES A. McCREA,
AUGUSTUS L. McCREA, AND HARRY COX, OF SAME PLACE.

IMPROVEMENT IN CARD-ENVELOPES.

Specification forming part of Letters Patent No. 117,818, dated August 8, 1871.

To all whom it may concern:

Be it known that I, CHARLES ROWLAND, of Washington, in the District of Columbia, have invented certain new and useful Improvements in Letter-Card Envelopes, of which the following is a specification, reference being had to the accompanying drawing.

The invention relates to that class of envelopes having a rigid or stiff back, to which is secured a flap to cover the inside surface thereof. The object of the invention is to furnish a surface that can be written upon without an underlying support or while held in the hand and then protected by a flap so gummed or otherwise secured to the card as that when sealed it covers the face of the card.

Figure 1 represents the flap, gummed as shown; Fig. 2, the card and flap attached.

A in the accompanying drawing is the back of the envelope, which should be of card-board or any other suitable material of sufficient rigidity. B is the flap on every side, with folds Z, each of which is gummed on the inside. That portion of the flap B between the folds Z should correspond with the surface to be covered thereby. One of the folds Z is secured to so much of the outside or back of the card A as it will cover, the edge of the card being placed in the crease of the fold.

The desired communication being written or printed upon the inside surface of the card, close the flap B thereon, moisten the gum upon the fold Z opposite the fold which is attached to the card, pass it over and seal it to the back of the

same, then moisten the remaining folds and seal them to the back of the card. The address may be written or printed and the postage-stamp affixed upon the outside of the flap B, which protects the face of the card from abrasion and at the same time conceals the communication. The flap and back may be made in one piece, either by so preparing the paper while being manufactured as to give a proper rigidity to the back, allowing the flap to be made thinner and flexible or by stiffening the back by the use of chemicals or otherwise. The parts may also be connected by rubber bands, eyelets, or rivets, or the flap may be secured to the back by splitting the lower edge of the latter and inserting the fold Z or a narrow strip thereof in such opening and then securing these parts together. The back of the card A may be used for advertisement or business-card, the folds Z being so formed as to leave a sufficient space between them when sealed for that purpose.

What I claim as my invention, and desire to secure by Letters Patent, is—

The combination and arrangement of a stiff or rigid back, A, with a flexible flap, B, substantially as herein described and shown.

In testimony that I claim the foregoing improvements in letter-card envelopes, as above described, I have hereunto set my hand and seal this 8th day of March, 1871.

CHARLES ROWLAND. [L. S.]
